UNITED STATES PATENT OFFICE.

W. O. DAVIS, OF PITTSBURGH, PENNSYLVANIA.

PRESS FOR MOLDING GLASS.

Specification of Letters Patent No. 10,470, dated January 31, 1854.

To all whom it may concern:

Be it known that I, WILLIAM OTIS DAVIS, of Pittsburgh, in the county of Allegheny and State of Pennsylvania, have invented a new and useful Improvement in Presses for the Manufacture of Glass; and I do hereby declare that the following is a full, clear, and exact description thereof, reference being had to the annexed drawings, forming 10 part of this specification, wherein—

Figure 1, is a perspective view of my improved press. Fig. 2 is a front elevation of my press with the lever pressed down. Fig. 3 is a similar view of my press with the lever 15 raised, the several parts of the press being marked on the drawings with letters of reference, similar letters being used for like parts in the several figures.

My invention consists in a combination 20 of a lever and toggle joint with a rocking shaft, swinging beam and connecting rods, in such a manner as that the pressure is always central and vertical, the parts being so arranged that little or no pressure or 25 strain is sustained by the frame work of the press, the whole pressure being sustained by the swinging beam, rocking shaft and the rods which connect them.

In the manufacture of pressed glass, it is 30 very important that the plunger, which enters the mold in which the glass is pressed, should enter the mold exactly vertically or parallel to the axis of the mold and that the downward motion of the plunger should be 35 exactly vertical, because the slightest inclination of the plunger from the vertical position will cause an inequality in the thickness of the article pressed, which will of course produce an inferior article. In 40 the pressing of tumblers, for instance, if the top of the plunger inclines but $\frac{1}{32}$ of an inch from a truly vertical position it will make one side of the edge of the tumbler when pressed $\frac{1}{16}$ of an inch thicker than the 45 other, which would render the tumbler unfit for use and even a much slighter variation would produce an unsalable article.

In lever presses of an ordinary construction, when the fulcrum is placed to one side 50 of the extremity of the lever to which the piston and plungers are attached, there is always more or less of a strain toward one side, tending to cause an inclination of the

piston rod from a vertical position, and the press, unless very strong and unwieldly will 55 yield slightly to this strain; and this variation, however slight, will, as we have seen, be duplicated in the mold; insomuch as what is taken off the glass on one side of the mold by the irregular pressure is added to 60 the other side. Should the guides through which the piston rod passes be strong enough to resist this side strain at first, they will 65 gradually wear away by the friction and the press soon become useless or require 70 frequent adjustings, besides the friction will prevent the press working as smoothly as it should, and will of course cause a loss of power. Again, in lever presses of an ordinary construction the pressure is only in 75 one direction and unless the bed plate on which the mold is placed is very strong and firm it will yield somewhat to the pressure, which will cause the mold to incline to one side, producing a like result, the axis of the 80 mold and plunger being no longer in the same vertical line. These practical defects in presses ordinarily used in the manufacture of glass are so great that a large percentage of articles made with such presses 85 are of an inferior quality. My improved press is designed to obviate these difficulties, first, by giving a vertical pressure to the piston rod which carries the plunger; second, by making an equal pressure from 90 above and below, so that the bed plate will not be liable to spring, having only the weight of the mold to sustain, and, thirdly, by disconnecting the fulcrum of the lever 95 from the frame work of the press, the only point of attachment of any part of the machinery by which the pressure is produced being to the bed plate at a point immediately under the center of the mold in the same vertical line as the axis of the piston 100 rod; the frame work of the press serving only as a guide to keep the piston rod and connecting rods in place.

Having thus explained the object to be attained by my improved press and generally the means by which I effect it, I will proceed to explain in detail its construction and operation, to enable others skilled in the art to make and use it.

In the several drawings α is the bed plate 105 of my press, made of polished iron and

large enough to serve as a table or bench to slide the mold on. This is supported by four legs *b*, *b*, &c., to which are attached wheels to enable the press to be readily moved from place to place. Attached to this bed-plate is a slight arch, consisting of two uprights *c*, *c*, and a cross piece *d* at top. These uprights *c*, *c*, have each a groove in the outer edge, to receive the rods *l*, *l*, which connect the rocking shaft *k* and swinging beam *m*.

Attached to the under side of the bed plate *a* at a point equidistant from the two uprights *c*, *c*, is a hollow cylindrical block *e* with a female screw cut in the inner surface of the cylinders to receive the screw *f*, which is turned by the wheel *g*, the screw working up and down inside of the cylindrical block *e*. At the lower extremity of the screw *f*, is a ball *h* (see Fig. 3) which works in the socket *i*, forming a ball and socket joint, the construction of which I need not more particularly describe. The socket *i* is in the center of the rocking shaft *k*, which extends across the press, immediately under the uprights *c*, *c*. To either extremity of this rock- ing shaft is attached by a pin the lower extremity of one of the connecting rods *l*, *l*, which pass upward between the projecting guide pieces *o*, *o*, partially entering the grooves in the uprights *c*, *c*. The upper extremity of these rods *l*, *l*, is attached by a hinge or pivot to the corresponding extremity of the swinging beam *m*. The swinging beam is made of two pieces, as in the drawing, or otherwise, as may be convenient, so as to inclose the toggle joint *n*, which works between the sides of the beam *m*. The toggle joint *n* is attached by a pin or pivot to the swinging beam *m* at a point in the beam not equidistant from either end, but removed to one side of the center, a distance equal to about one half of the toggle joint or short arm of the bent lever. The lower end of the toggle joint is attached by a pin or pivot to the head of the piston rod *p*. Attached to the toggle joint is the working lever *q* and at right angles to the lever or nearly so is a counterpoise *r*, to aid in throwing back the lever. To the end of the piston rod is fixed the sliding frame *s*, through which passes a screw *t*, which is a continuation of the piston rod *p*. The sliding frame *s*, works up and down between the uprights *c*, *c*, the inner edges of which serve as guides or ways which are planed true and smooth for the sliding frame *s* to work in. A plate of iron *u* of the shape shown in Fig. 1, with a circular hole in the center, large enough to allow of the passage of the plunger of the mold, which is attached to the extremity of the piston rod, slides between the sliding frame *s* and between the uprights *c*, *c*. On this plate *u* are four uprights *v*, *v*, &c., and on these up-

rights is placed another plate *u'* of similar shape to the plate *u*, the ends of which slide in the sides of the sliding frame *s*. These two plates *u* and *u'* are kept apart by the springs *w*, *w*, &c., which surround the uprights *v*, *v*, &c. The screw *t*, passes through the center of the upper plate *u'* and the wheel *x*, which works on the screw *t*, regulates the height of the bottom plate *u*, to adjust the press to any size of mold to be used, so that when the plate *u* rests on the top of the mold the plunger will be at the right height. A further adjustment of the height of the lower plate *u*, is attained by means of the wheel *g* working on the screw *f*, by means of which the rocking shaft *k* and with it the sliding frame *s* (to which it is attached by the connecting rods, swinging beam, toggle joint, and piston rod) are raised or lowered. By means of these adjusting screws the height of the sliding frame *s* is so adjusted as that when the lever is brought so far down that the lower plate *u* rests on the top of the mold the remaining part of the descent of the lever will be sufficient to press the plunger to the requisite depth in the mold. When the lower plate *u* rests on the top of the mold, it can, of course, descend no farther, but by drawing the lever still farther down the sliding frame *s*, (to which the plunger is attached,) with the upper plate *u'*, will descend still farther, compressing the spring *w*, *w*, &c. When the pressure is removed from the end of the lever *q*, the springs will raise the plunger out of the mold. The lever is then thrown back by hand, the mold is removed and after the glass is withdrawn it is again replaced and the same operation is repeated.

Now it is manifest from what I have stated that there is in my press very little or no strain on the uprights *c*, *c*, or cross piece *d*, but that the pressure is borne by the rocking shaft, swinging beam, and connecting rods. If the swinging beam did not move freely from one side to the other there would be, but any side strain on the piston rod as it passes through the cross piece *d*, is at once relieved by the swinging beam coming over until the center pin of the toggle joint is in the same vertical line as the axis of the piston rod, at which time the pressure is greatest; also that as the point of connection of the cylindrical block *e*, to which the rocking shaft is attached by the ball and socket joint, is immediately under the axis of the piston rod the bed plate is during the pressure pressed between the bottom of the mold and the cylindrical block *e*, and suffers no strain whatever, and the nearer the parts arrive at the point of greatest pressure the more nearly is the pressure in a vertical line.

Having thus described my improved press,

what I claim as my invention and desire to secure by Letters Patent is—

The combination of the rocking shaft, connecting rods swinging beam and toggle joint lever or their mechanical equivalents as hereinbefore described for the purpose of procuring a vertical pressure in presses, to-

gether with the mode of attaching them so as to relieve the bed plate and frame work of the press of any strain.

WM. O. DAVIS.
